UNITED STATES PATENT OFFICE.

RICHARD H. VESEY, OF DENVER, COLORADO.

DESIGN FOR A PESSARY.

SPECIFICATION forming part of Design No. 33,362, dated October 16, 1900.

Application filed September 1, 1900. Serial No. 28,847. Term of patent 14 years.

To all whom it may concern:

Be it known that I, RICHARD H. VESEY, a citizen of the United States of America, residing at Denver, in the county of Arapahoe and State of Colorado, have invented and produced a new and original Design for Pessaries; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to a new and original design for pessaries; and it consists of the features hereinafter described and claimed, all of which will be fully understood by reference to the accompanying drawings, in which is illustrated an embodiment thereof.

20 In the drawings, Figure 1 is a perspective view of a pessary, showing my new design.

Fig. 2 is a section taken through the middle of the device, taken on the line *x-x*, Fig. 1. Fig. 3 is a similar section taken on the line *y-y*, Fig. 1.

As shown in the drawings, the leading or material feature of my design consists of a cup-shaped member A and a star-shaped member B applied to the member A exteriorly, the member B being thicker in cross-section than the member A.

Having described my invention, what I claim as new, and desire to secure by Letters Patent, is—

The design for a pessary as herein shown and described.

In testimony whereof I affix my signature in presence of two witnesses.

RICHARD H. VESEY.
